(57) **CLAIM**

The ornamental design for the cooking pots and stoves for camping, as shown and described.

DESCRIPTION

FIG. 1 is a perspective view of a cooking pot and stove for camping showing the new design including a pot, a lid, and a stove and with a handle on the pot in an opened position; FIG. 2 is a perspective view the embodiment of FIG. 1 with the handle in a folded position;

FIG. 3 is a front elevation view of the embodiment of FIG. 1;

FIG. 4 is a rear elevation view of the embodiment of FIG. 1;

FIG. 5 is a left side elevation view of the embodiment of FIG. 1;

FIG. 6 is a right side elevation view of the embodiment of FIG. 1;

FIG. 7 is a top plan view of the embodiment of FIG. 1; and, FIG. 8 is a bottom plan view thereof of the embodiment of FIG. 1.

Broken lines in FIGS. 1–8 illustrate unclaimed portions of the first embodiment of a cooking pot and stove for camping and form no part of the claimed design.

1 Claim, 8 Drawing Sheets
